STRIP SHINGLE

Application filed May 4, 1939. Serial No. 380,375.

This invention relates to roofing elements or shingles and more particularly to an improved form of flexible composition roofing strip of the type wherein notches or recesses are utilized to define tabs simulating separate shingles when a number of the strips are laid on a roof.

Perhaps the most common form of roofing strip, now used, is that wherein narrow notches or slots are formed in the weather exposed area to define shingle-simulating tabs. These strips, as is well known, are laid up on the roof in successive overlapping courses with the adjacent strips of each course arranged side by side and with the overlapping strips of each course in staggered relation with respect to the strips of the preceding course. When shingles of this type are thus arranged on a roof, the slots or notches necessarily expose a corresponding area of the normal concealed or overlapped portions of the underlying strip, and water seeping or blowing in under the strips, especially near the upper ends of the slots, is very liable to reach the roof supporting structure unless the strips are sufficiently wide to underlap the shingles of the succeeding course for a considerable distance beyond the upper ends of the slots therein.

The principal object of my invention resides in the formation of shingle strips in such a manner that the tab-defining slots thereof as well as the joints between adjacent strips in a course, are sealed or closed off so as to avoid the possibility of water gaining entrance beneath the upper ends of the slots, or through the joints.

A further object of the invention is to provide the strips with closure elements for the tab-defining slots secured to the under-surface of the strips, in such relation to the tab-defining slots as to realize the principal object of the invention as aforesaid.

With the above and other objects in view, which will appear as the description proceeds, my invention consists in the novel construction, arrangement and combination of various elements and parts described in the following specification and illustrated in the accompanying drawing. While I have il-

lustrated and will describe certain preferred embodiments of the invention, it will be understood that such variations or modifications thereof may be made as will fall within the scope of the appended claims. 55

In the drawing, Figure 1 is a plan view of one form of my improved shingle strip,

Figure 2 is an edge view thereof, Figure 3 is a plan view showing a slightly 60 modified construction.

The strips, according to my invention, are formed of flexible water-resistant fibrous base, such as the ordinary asphaltic felt-base roofing fabricated from sheets of rag, asbestos or similar fibers. These sheets are rendered water-resistant by impregnating them with asphalt or the like, and one or both surfaces thereof are then supplied with a coating layer of weather resistant material such as blown asphalt having a melting point approximately 220° F. Mineral surfacing such as crushed slate is partially imbedded in the coating layer on the surface to be exposed on the roof, and when the opposite surface of the sheet also has a coating layer, the latter is generally provided with a surfacing of fine mineral such as talc or mica. 70 75

As shown, the shingle strip is indicated generally by the numeral 10 and comprises an upper portion 11 which is the unexposed or concealed part of the strip when laid, and a lower or weather exposed area 12. The exposed portion 12 is formed with shingle simulating tabs 13 defined from each other by spaced vertical intermediate slots 14, and terminal notches 14a, which are preferably made in the sheet at an appropriate stage of its fabrication prior to the severance of the strips 10 from the sheet. The tab-defining slots or notches 14, 14a, may be spaced apart at equal distances so as to provide shingle simulating tabs of equal width, or they may be spaced apart at variable distances as shown, so as to form tabs of varying widths. 80 85 90 95

In accordance with the invention, narrow bands or strips of flexible waterproof material, such as saturated or saturated and coated roofing felt, are secured to the under-face 15 of the strips 10 so as to surround and 100

form closures for the tab-defining slots or notches.

In the form shown in Figure 1, bands or strips 16, of a length corresponding to the height of the shingle strip and of a width sufficient to extend beyond the side edges of slots 14, are secured to the bottom face of the strip 10 in position to underlie the slots 14. At one end of the strip, I secure a somewhat wider band 17, to the underface of the strip, leaving a portion of the band 17 projecting beyond the side edge of the shingle strip 10. The strips 16 and 17 may be affixed to the shingle strips by any suitable adhesive such as molten asphalt, or aqueous dispersion of asphalt or the like. In Figure 3, the construction is modified only to the extent that the closure bands or strips 16a, 17a, corresponding to the strips 16, 17, respectively, of Figures 1 and 2, are made shorter, and extend only from the butt-edge of the shingle strips to a point slightly above the upper end of the tab-defining slots 14, 14a, instead of extending all the way to the upper edge of the shingle strip.

The shingle strips may be laid on the roof in the customary fashion, with the projecting portions of the terminal bands 17 or 17a lapped by the opposite end of an adjoining shingle. When two adjoining shingle strips are thus laid together side by side, the notches 14a at the opposed ends of the strips complete the appearance of the tab-defining slots at the ends of the strips, while the bands or strips 17, 17a, effectively seal the same in the manner described. If desired, adhesive material may be applied to the lapped portions of the end bands to aid in securing the same to the underface of the adjoining shingle strip, but in any event, the securing nails for the shingle strips are driven through the same at points slightly above the upper ends of the slots so as to pass through the sealing strips.

As a further feature of the invention, the upper surface of the sealing or closure bands may be left unsurfaced or they may carry partially embedded crushed mineral grit of dark color in comparison to the color of the mineral grit affixed to the exposed face of the shingle strip, thus greatly accentuating the individual shingle-simulating effect of the slots. Furthermore, when the strips are applied on the roof, water that may collect in the channel formed by the tab-defining slots and the underlying closure strip will pass downwardly under the influence of the natural pitch of the roof and drain onto the surface of the sub-adjacent strip. Accordingly, instead of the usual construction wherein water may creep or be blown up under the shingles through the tab-defining slots, I provide by my invention a construction in which a definite sealed path forms a

positive drain for water reaching and collecting in the slots.

The sealing strips will preferably be of less thickness than the shingle strip itself so as not to elevate the exposed portion of the shingles materially above the surface of the underlying shingles in the preceding course.

Shingle strips constructed in accordance with my invention also afford certain advantages when subjected to a recoating and resurfacing operation of the type set forth in the Patent Number 1,612,776 to Lester Kirschbraun. In accordance with the said patent shingles or shingle strips are subjected to reimmersion in asphaltic coating material in order to encase the weather exposed surfaces and edges of the shingle elements in a protecting layer of weatherproof material, the recoated areas being also preferably surfaced with crushed mineral of a suitable variety. In the practical manufacture of strips in accordance with the said Kirschbraun patent, the treatment provided by said patent is generally reserved for shingle "seconds", that is to say, shingles as ordinarily produced but which carry slight imperfections or irregularities which do not perceptibly affect the life of the shingle and which are objectionable only from the viewpoint of appearance. The recoating and resurfacing operation accordingly provides an effective means for reclaiming shingle "seconds" and converting them into a more desirable type of shingle, this being advantageous also from the standpoints that the exposed surfaces and edges are sealed against the action of the elements, and further that the recoated and resurfaced elements present an increased thickness of highly desirable texture along the butt edges thereof.

In thus reclaiming shingle "seconds", it frequently happens that the shingle to be retreated is of a light color and the mineral surfacing used in the retreating operation is of a dark color. In these cases, therefore, when the retreated shingles are laid upon the roof, the light color of the upper portion of the shingles, (the retreating operation not being applied to these portions), is visible through the slots of the overlying shingles and this is frequently objectionable and heretofore has been overcome only by a careful and tedious selection of the color of the shingles to be retreated in accordance with the color of the mineral to be used in the retreating operation. In the shingle strips as provided by my invention, on the other hand, the sealing strips conceal the mineral surfacing on the upper portions of the underlying strip, and hence shingles constructed in accordance with my invention, may be retreated in accordance with the said Kirschbraun patent without reference to their original color.

The shingle strip construction of my invention also affords certain advantages in

connection with the production of shingles, the exposed areas whereof are formed with a layer of copper by electrodeposition. In the actual practice of electrodepositing copper on mineral surfaced prepared roofing shingles, the deposition of copper is confined substantially to the areas to be exposed, as otherwise the cost would be prohibitive. In electrodepositing copper upon shingles of 5 the square butt variety, it is necessary to deposit the copper not only upon the lower portions of the shingles which form the weather-exposed areas thereof, but also to form an electrodeposited tongue of copper on 10 the upper portions of the shingle intermediate the tab-defining slots, so that when the shingles are applied in courses on the roof, these tongues of copper will underlie the slots and be visible therethrough. The electrodeposition of these separate tongues extending into the upper areas of the shingles, involves a rather sensitive operation in commercial practice and represents a costly element of the manufacture. The necessity for 20 thus plating the tongues of copper may be avoided with shingles constructed in accordance with my invention, for, as will be noted, when the lower or weather-exposed areas of 25 my strip shingle are made electroconductive, and then passed through an electroplating bath, the copper will be deposited not only upon the surface of the tabs 13, but also upon the surface of the sealing strips exposed 30 through the slots 14, 14a, so that when these 35 electroplated copper shingles are applied on the roof, the entire visible exposed surface will carry the copper coating and hence there is no necessity for plating tongues of copper in the upper areas of the shingle as heretofore.

If desired, in some instances, the tab-defining slots 14 may be formed at an inclination to the vertical, instead of perpendicularly to the butt-edges of the strips. 45 Having thus described my invention, it will be understood that numerous changes and modifications may be made therein without departing from the spirit of the invention as defined in the subjoined claims.

50 I claim as my invention:

1. A roofing element comprising a body portion and spaced sealing strips secured to the underface of the body portion, the body portion being formed with tab-defining slots 55 in the weather-exposed areas thereof, said slots cut therethrough being confined to portions of the weather-exposed areas which are underlaid by said sealing strips.

60 2. A shingle strip comprising a body portion formed with spaced slots cut through the exposed areas thereof, spaced sealing strips adhering to the undersurface of said strip directly beneath said slots and a sealing strip adhering to the undersurface of 65 said strip near one of its lateral edges and

extending a substantial distance beyond said edge.

3. As an article of manufacture, a shingle strip having spaced slots cut through the lower portion thereof to form a plurality of tabs, spaced sealing strips of less thickness than the shingle strip fastened to the lower face of said strip under each slot and a sealing strip fastened to the undersurface of said shingle strip near one of the lateral edges 70 thereof so as to extend a substantial distance beyond said lateral edge. 75

Signed at Rutherford in the county of Bergen and State of New Jersey this third day of May, A. D. 1929. 80
